CONCRETE ARCH CONSTRUCTION

Charles S. Whitney, Milwaukee, Wis.

Application May 4, 1942, Serial No. 441,681

7 Claims. (Cl. 108—1)

This invention relates to reinforced concrete roof arches of the type in which spaced arch ribs are arranged to carry intervening roof slabs, and it resides in an improved form of such roofs in which the locus of attachment of the roof slabs to the arch ribs is disposed sufficiently near the neutral axis of the ribs to substantially reduce the contribution of stress from the roof slab material to the ribs or from the ribs to the roof slab upon flexure of the roof in response to loading and volume changes.

One of the objects of this invention is to provide a reinforced concrete arched roof which reacts with smaller thrusts when its extremities are displaced relative to one another, or which, when its extremities are restrained, imposes smaller thrusts due to volume changes upon the restraining abutments.

Another object of this invention is to effect a substantial saving in the quantity of concrete and steel required in an arched roof of a given size.

Another object of this invention is to increase the distance which can be economically spanned by a reinforced concrete arched roof of the type here involved.

Another object of this invention is to substantially reduce the amount of cracking of the roof slab by reducing the amount of tensile stress which is imposed thereon.

The above and other objects and advantages of this invention will appear from the description of the invention which follows.

Heretofore in the art, reinforced concrete roof arches which are restrained at their spring lines by abutments have been constructed to present either a smooth exterior shell or barrel, or a smooth interior shell or barrel, that is to say the intervening roof slabs have been secured to the arch ribs either at or near their upper or lower extremities. This practice has been detrimental to structural economy of such arches because it concedes little to the important fact that in a structure of this sort and of optimum economy a substantial measure of non-destructive yielding or elasticity must be preserved in the arch rib. This is because concrete is subject to substantial volume changes in response to alterations in ambient temperatures and moisture conditions. When these changes occur the thrusts in the arch change in much the same manner as they would change if the abutments were moved toward or away from one another.

In structures of the type here involved reliance upon the tensile strength of the thin roof slab to contribute to the necessary load sustaining

strength of the rib skeleton is not accepted as sound practice. While the strength contributing capacity of the slab acting in tension must be ignored it is equally imperative that the compression sustaining capabilities of the slab be taken into account in determining the tension stresses which arise on bending in the parts of the ribs on the opposite side of the neutral axis. This is of importance because tensile stresses due to bending arising out of thrusts caused by volume changes increase with an increase in the moment of inertia of the section of the effective rib and this section must include not only the section of the rib itself but also the section of the adjoining roof slabs.

The stiffness of the rib, taking into account the effect of the roof slab is therefore greater than the stiffness which is credited to the rib for load sustaining purposes. From this it follows that an isolated rib in which the extremities are restrained by abutments and which is designed for optimum economy is inadequate to sustain the thrusts due to volume changes when the roof slab is attached thereto in a position where the moment of inertia of the effective rib section is largely augmented. The problem created by this relationship has heretofore been dealt with by disposing sufficient material, in the part of the rib on the side of the neutral axis opposite the slab, to hold the tensile stresses in the rib within safe limits. This adds further to the stiffness of the arch and in arches, the extremities of which are restrained, the thrusts against the abutments due to volume changes are increased accordingly. This in turn calls for stronger abutments and entails more elaborate footings and foundations designed to provide for an inevitably increased measure of foundation yielding.

In contrast, I have discovered that the roof slab may be attached to the rib at or near the neutral axis of the rib and when this is done the moment of inertia of the effective rib section is little different from that of the rib alone and little or no material need be added to the rib to withstand the augmentation of the thrusts due to volume changes which become effective upon attaching the slab. The savings thus effected may amount to a very considerable part of the material required for any given structure. This saving extends not only to the ribs but also to the abutments and foundations and is accentuated in arch roofs of large span such as may be used for sports arenas, airplane and airship hangers, public meeting halls and the like. Not only is a saving in material made possible by this invention but the

distance which may be economically spanned by a reinforced concrete arch roof has been increased and cracking of the roof slab has been reduced through its application.

This invention is herein described by reference to the accompanying drawings which form a part hereof and in which there is set forth by way of illustration and not of limitation one conventionalized instance of a structure embodying this invention.

In the drawings:

Fig. 1 is a perspective view, partly broken away, of a building constructed in accordance with this invention;

Fig. 2 is a detailed sectional view in side elevation, viewed through the plane 2—2, indicated in Fig. 1; and,

Fig. 3 is a detailed sectional view in front elevation viewed through the plane 3—3, indicated in Fig. 1.

The structure illustrated in Fig. 1, represents an instance of this invention embodied in the side-walls and roof portions of a conventionalized building, although the invention is adapted to structural shells of a wide variety of forms. In the structure shown, a plurality of spaced, parallel arch ribs 1, spring from rigidly fixed abutments formed from vertical columns 2 and struts or buttresses 3. The columns 2, and the buttresses 3 extend below ground level to appropriate footings not shown. The arch ribs 1 are thus restrained by the abutments and therefore must flex in response to volume changes caused by thermal expansion, moisture changes, shortening under load and similar effects. The ribs 1 as shown as well as the columns 2 and buttresses 3 are made up of concrete reinforced by steel located and proportioned as shown or in any suitable manner.

Disposed between the ribs 1 and secured thereto are roof slabs 4. The slabs 4 are also made up of reinforced concrete which may be poured integrally with the ribs as shown or may be separately formed and secured to the ribs in any convenient manner. The slabs 4 are located with respect to the ribs 1 at a zone which embraces the cylindrical surface defined by the neutral axis of the ribs 1. This clearly appears in the two detailed sectional views, Figs. 2 and 3. By thus locating the slabs 4, which are much thinner than the vertical dimension of the ribs, the capacity of the ribs 1 to flex in a vertical direction is little affected.

From the above it will be seen that when slabs are secured to ribs as they are in prior structures at either the upper or lower extremities of the ribs the effective rib is greatly stiffened as compared with the structure of this invention and the stress in the portions of the ribs remote from the slabs is greatly augmented for any given amount of deflection in the roof. Since the amounts of such deflections are fixed by the physical constants of the concrete such as its coefficient of thermal expansion and the like, the increased stiffness in the rib cannot act to diminish the deflection to any appreciable extent. As a result higher thrusts and higher stresses resulting from volume changes are inevitable. The novel roof structure of this invention, however, avoids these augmented stresses by locating the roof slabs in the vicinity of the neutral axis of the rib. When this is done the moment of inertia of the section of the effective rib is very little greater than that of the rib itself. This is particularly true because the depth of the slab is

usually less than one fourth the depth of the rib. As a result the rib is free to act in bending much as though the roof slab were absent. This reduced participation of the roof slab in the bending action of the rib also is of marked advantage from the standpoint of the amount of tension cracking to be expected in the roof slab. With the slab located in accordance with this invention little tensile stress is imposed upon the slab upon bending of the rib, and cracking from this cause is practically eliminated.

By constructing for greater flexibility rather than greater rigidity, the normal and expected course has been departed from in this invention and by following this contrary path a stronger and more economical structure is arrived at.

While this invention has been herein described by references to one specific instance of its embodiment it is intended that this instance shall not unnecessarily limit the protection to be afforded hereby, the intent being that the protection to be afforded hereby shall extend to the full limit of the inventive advance disclosed herein as defined by the claims hereto appended.

I claim:

1. In a reinforced concrete arched roof, the combination comprising a plurality of spaced parallel reinforced concrete arch ribs said ribs having a cross section the vertical dimension of which is substantially greater than the horizontal dimension thereof, a pair of restraining abutments for each rib anchored against outward movement whereby accommodation for volume changes in the material of the ribs is accomplished to a substantial extent by bending of said ribs, said abutments being rigidly attached to said ribs, and reinforced concrete roof slabs of arched configuration conforming to the curvature of said ribs disposed between said ribs and secured thereto throughout the extent of said slabs at a zone which embraces the neutral axis of said ribs, said slabs having a thickness less than one fourth the vertical dimension of the cross section of said ribs.

2. In a reinforced concrete arched roof, the combination comprising a plurality of spaced parallel curved reinforced concrete arch ribs, a pair of restraining abutments for each rib anchored against outward movement whereby accommodation for volume changes in the material of the ribs is accomplished to a substantial extent by bending of said ribs, and roof slabs of arched configuration conforming to the curvature of said ribs disposed between said ribs and attached thereto throughout the extent of said slabs along zones intermediate the inner and outer faces of said ribs in position to embrace the neutral axis of said ribs.

3. In an arched roof the combination comprising a plurality of spaced parallel curved arch ribs, a pair of restraining abutments for each rib anchored against outward movement whereby accommodation for volume changes in the material of the ribs is accomplished to a substantial extent by bending of said ribs, and roof slabs of arched configuration conforming to the curvature of said ribs disposed between said ribs and attached thereto throughout the extent of said slabs along zones intermediate the inner and outer faces of said ribs in position to embrace the neutral axis of said ribs.

4. In a reinforced concrete arched roof, the combination comprising a plurality of spaced parallel curved reinforced concrete arch ribs, a pair of restraining abutments for each rib anchored against outward movement whereby accommoda-

tion for volume changes in the material of the ribs is accomplished to a substantial extent by bending of said ribs, and reinforced concrete roof slabs of arched configuration conforming to the curvature of said ribs disposed between said ribs and attached thereto throughout the extent of said slabs along zones intermediate the inner and outer faces of said ribs in position to embrace the neutral axis of said ribs.

5. In a reinforced concrete structure the combination comprising a plurality of arch ribs of reinforced concrete, abutments for said ribs anchored against outward movement whereby accommodation of volume changes in the rib material is accomplished to a substantial extent by bending of said ribs, and a roof shell disposed between said ribs and secured thereto midway between the inner and outer faces thereof in position to embrace the neutral axis of said ribs.

6. In a reinforced concrete arched structure, the combination comprising a plurality of spaced parallel curved reinforced concrete arch ribs, a pair of restraining abutments for each rib anchored against outward movement whereby accommodation for volume changes in the material

10 of the ribs is accomplished to a substantial extent by bending of said ribs, and roof slabs of arched configuration conforming to the curvature of said ribs disposed between said ribs and attached thereto within that area of the ribs intermediate and upper and lower surfaces where said ribs are substantially free of deformation due to simple bending.

15 7. In a reinforced concrete arch structure a plurality of spaced parallel curved reinforced concrete arch ribs having a radial depth of cross section greater than the breadth thereof, a pair of abutments for each rib anchored against outward movement whereby accommodation for volume changes in the material of the ribs is accomplished to a substantial extent by bending of said ribs, and a roof slab of a depth not more than one-fourth the depth of said ribs of arched configuration conforming to the curvature of said ribs and disposed between the same and attached thereto within that area of the ribs intermediate and upper and lower surfaces where said ribs are substantially free of deformation due to simple bending.
